UNITED STATES PATENT OFFICE.

JOSEPH M. STABEL, OF ROCHESTER, NEW YORK, ASSIGNOR TO DOMESTIC APPLIANCES COMPANY, OF ROCHESTER, NEW YORK, A CORPORATION OF NEW YORK.

CLEANING-TOOL.

1,139,736.

Specification of Letters Patent. Patented May 18, 1915.

Application filed October 16, 1912. Serial No. 726,165.

To all whom it may concern:

Be it known that I, JOSEPH M. STABEL, a citizen of the United States, and resident of Rochester, in the county of Monroe and 5 State of New York, have invented certain new and useful Improvements in Cleaning-Tools, of which the following is a specification.

This invention relates to cleaning-tools, 10 particularly such as are employed in cleaning floors and floor-coverings, and in which a head or operating-member is mounted upon a long shaft or handle by which it may be moved over the surface to be cleaned.

15 The invention is particularly applicable to tools, of the type in question, such as are employed in connection with vacuum-cleaning systems, although the invention in certain aspects may be usefully applied to tools 20 of other types.

The object of the invention is to produce a cleaning-tool which may be conveniently used under and around furniture, as well as upon open floor-spaces. To this end I employ, in combination with a head, and a 25 handle or shaft pivotally connected therewith, so as to be angularly adjustable in a vertical plane, means mounted upon the shaft and manually-operable by the user of 30 the tool to adjust the angle between the head and the shaft, or to fix these parts in adjusted position. In this manner the tool is adapted to be used normally with the handle at a convenient inclination to the floor, while, 35 in working under furniture, the handle may be adjusted to occupy a more nearly horizontal position, and in either position of the handle the tool may be held at the proper angular relation with the handle to cause its 40 operative extremity to be presented evenly against the floor-surface.

In the accompanying drawings:—Figure 1 is a side-elevation of a cleaning-tool embodying the present invention, the figure 45 showing in full lines the normal position of the parts, and in dotted lines the position assumed when the tool is used under low furniture; Fig. 2 is a bottom-view of the tool of Fig. 1, with the parts adjusted to an 50 intermediate position and shown partly in horizontal median section; Fig. 3 is a vertical median section through the pivotal joint which connects the head and the shaft; and Fig. 4 is a section, on the line 4—4 in Fig. 2,

looking from right to left in the latter 55 figure.

The invention is illustrated as embodied in a vacuum-cleaning tool having a hollow head, of ordinary form, provided with the usual slot or orifice 6, the tool being intended for use with the lips which surround or define this orifice pressed closely against the surface of a carpet or other floor-covering. This head 5 is provided with the usual tapered nipple 7 for connecting it with a tubular handle or shaft.

The tubular shaft 8 is of ordinary form, having at its forward end the usual tapered sleeve 9 for connection with the head, and at its rear end a tapered nipple 10 for connection with the vacuum-hose. The nipple 7 and the sleeve 9 are not, however, joined together in the usual manner, but between these parts is interposed a pivotal joint embodying features of the present invention. 75 The joint just referred to comprises a socket-member 11 having a tapered sleeve 12 adapted to form a slip-joint with the nipple 7 of the head 5. This socket-member has a substantially hemispherical socket which receives a spherical ball-member 13, and this ball-member is provided with a tapered nipple 14 adapted to form a slip-joint with the sleeve 9 on the shaft 8. The ball-member is also provided, as shown in the drawings, 80 with a longitudinal air-passage which connects the shaft and the head in all positions of the joint.

In order to secure the ball-member and the socket-member in operative relation, a 90 fastening-member is employed in the form of a ring 15, which surrounds and is slideable upon the periphery of the socket-member. This ring is connected with the ball-member by two pivot-pins 16, which are 95 fixed in the ball-member at the extremities of a horizontal diameter thereof, the socket-member being recessed, as shown in dotted lines in Fig. 3, to receive the pins. The ring 15 has an annular shoulder 17 which bears 100 against the pivot-pins. By means of screws 18 passing through the ring and threaded into the socket-member the ring may be drawn against the pivot-pins in such a manner as to force the ball-member closely 105 against its seat in the socket-member. The pivot-pins thus serve the function of maintaining the bearing-surfaces of the joint in

engagement, while any wear between these surfaces may be taken up by means of the screws 18. The pins serve the further purpose of limiting the relative movement of 5 the ball- and socket-members to a pivotal movement about a horizontal axis, since movement in any other direction is prevented by the inter-engagement of the pins with the sides of the recesses in the socket-member. Accordingly, the joint provides 10 for relative angular adjustment of the shaft and the head in a vertical plane. While the use of spherical engaging surfaces is not essential in a joint having its movements limited as just described, I find that the construction in question facilitates the manufacture of the device, since the bearing-surfaces may be produced in each case by a single turning operation, and it has the further advantage that lost motion in all 15 directions between the parts of the joint may be taken up by a single adjustment, thus providing effectually against wear in the mechanism. The use of the pivot-pins in connection with the spherical bearing-members has the further advantage that it produces less friction between the parts than in the case of the usual spherical joint, wherein the ball-member is retained against 20 its seat by means of a retaining-device having an annular bearing or seat against the ball-member.

The pivotal joint just described is useful in connection with cleaning-tools having 35 heads of various forms, including those in which the head has a bearing-surface against the floor which is so wide that it maintains itself in proper engagement therewith without the necessity of fixing the head and the shaft in their relative angular position. In connection with comparatively narrow devices, however, such as the head 5, it is necessary that the proper engagement of the head with the floor-surface be maintained by a fixed connection with the shaft. Accordingly the illustrated tool is provided 40 with manually-operable means for adjusting and fixing the relative positions of the joint-members. To this end a sleeve 20 surrounds the shaft 8, being mounted loosely and rotatably thereon. This sleeve is fixed against longitudinal movement, at its lower end, by engagement with the shoulder formed by the sleeve 9, while its upper end abuts 45 against a sleeve 21 integral with the nipple 10. The upper extremity of the sleeve 20 is knurled or roughened, as at 22, to provide a hand-hold by which it may be conveniently rotated, and upon the lower end of 50 the sleeve is fixed a collar 23 having an integral radially-projecting arm 24. This arm is bifurcated or recessed to receive the ball-shaped rear-end of an arm 25 which projects rearwardly from the fastening-ring 15 55 on the socket-member of the pivotal joint.

By rotating the sleeve 20 the arm 24 is rocked in such a manner as to rock the arm 25, and cause a pivotal movement of the members of the joint. After such adjustment there is sufficient friction between the 70 parts to maintain the pivotal joint in its adjusted position. Accordingly, whether the shaft be in either of the positions shown in Fig. 1, or in any intermediate position, the head 5 is held in its angular relation with the shaft with sufficient firmness to permit its use in the ordinary manner. In working around furniture, therefore, it is necessary, in order that the tool may be used under such furniture, merely to rotate the 75 sleeve 20 partially upon the shaft, whereupon the shaft may be dropped to horizontal position while the head of the tool still engages the floor-surface properly. To prevent the parts from moving too far and to 80 maintain the arms in proper engagement a stop-shoulder 19 is formed on the ball-member 13, this shoulder being adapted to engage the ring 15 in either extreme position 85 of the pivotal joint.

By articulating the arms 24 and 25 in the manner above described, and employing these arms in connection with a shaft and a joint-member having a slip-joint such as that provided by the sleeve 9 and the nipple 95 14, the pivotal joint is rendered adaptable for use with cleaning-tools of various forms. If, for example, it be desired to substitute, for the head 5, a head having a wide, flat bearing-surface, such, for example, as is 100 employed upon a hardwood floor, the shaft may be disengaged from the pivotal joint by disconnecting the slip-joint in question, and by the same operation the arms 24 and 25 are disengaged. The shaft and the pivotal joint may then be connected again in 105 such a position that the arms are out of engagement with each other. The pivotal joint is then freely movable, thus permitting the shaft to swing freely in a vertical 110 plane, as is desirable in using a floor-cleaning tool of the kind above referred to.

My invention is not limited to the embodiment thereof hereinbefore described and illustrated in the accompanying drawings, 115 but may be embodied in various other forms within the nature of the invention, as it is defined in the following claims.

I claim:—

1. In a cleaning-tool, the combination, 120 with a hollow head and a tubular shaft angularly adjustable in a vertical plane, of a manually-rotatable sleeve surrounding the shaft, and connections between the sleeve and the head adapted to produce angular adjustment of the head when the sleeve is rotated upon the shaft.
2. In a cleaning-tool, the combination, 125 with a hollow head and a tubular shaft angularly adjustable in a vertical plane, of a 130

manually-rotatable sleeve surrounding the shaft, and inter-engaging arms connected with the head and the sleeve whereby the head is angularly adjusted by rotation of 5 the sleeve.

3. In a cleaning-tool, the combination of a pivotal joint comprising two members, the first of said members being adapted for detachable connection with a cleaning-head; 10 a tubular shaft connected, by a slip-joint, with the second of said members; and manually-operable means, mounted upon the shaft, for producing angular adjustment of the joint, said means having operative connections with the first joint-member which 15 are disengageable when the shaft is disengaged from the second member at said slip-joint.

4. In a cleaning-tool, the combination of 20 a pivotal joint comprising two members, the first of said members being adapted for connection with a cleaning-head; a shaft connected with the second joint-member; a manually-rotatable member journaled on 25 the shaft; and connections between the first joint-member and the manually-rotatable member comprising inter-engaging arms, for angularly adjusting the head and the shaft about said joint, one of the arms having 30 a recessed extremity which embraces the extremity of the other arm.

5. In a cleaning-tool, the combination of a pivotal joint comprising two air-conducting joint-members, the first of said members being adapted for connection with a cleaning-head; a shaft removably connected with the second joint-member; a member journaled longitudinally on the shaft and manually rotatable; and interengaging means connecting the first joint-member and the 35 rotatable member whereby rotation of the latter may cause angular movement of the pivotal joint, said connecting means being disengageable when the shaft is removed from the second joint-member. 40

6. In a cleaning-tool, the combination of a pivotal joint comprising two air-conducting joint-members, the first of said members being adapted for connection with a cleaning-head; a tubular member connected with 45 the second joint-member but rotatable relatively thereto, the outlet passage from said second joint-member extending through said tubular member; and connections between the tubular member and the first 50 joint-member whereby rotation of the tubular member may cause angular movement between the joint-members. 55
